MARK A. RICE, OF LOS ANGELES, CALIFORNIA.

ROTARY ENGINE.

SPECIFICATION forming part of Letters Patent No. 744,614, dated November 17, 1903.

Application filed July 8, 1903. Serial No. 164,348. (No model.)

To all whom it may concern:

Be it known that I, MARK A. RICE, a citizen of the United States, and a resident of Los Angeles, in the county of Los Angeles and State of California, have invented a new and Improved Rotary Engine, of which the following is a full, clear, and exact description.

The object of the invention is to provide a new and improved rotary engine which is simple and durable in construction and arranged to insure easy running, to allow of cutting off the motive agent at any desired point, to permit reversing the engine, to prevent end-wise thrust of the piston in the cylinder and to utilize the motive agent expansively to the fullest advantage.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement on the line 1 1 of Fig. 2. Fig. 2 is an end elevation of the same. Fig. 3 is a transverse section of the same on the line 3 3 of Fig. 1. Fig. 4 is a like view of the same on the line 4 4 of Fig. 1. Fig. 5 is an enlarged longitudinal sectional elevation of the cylinder, the piston, and the piston-heads; and Fig. 6 is a diagrammatic view showing the inlet and exhaust ports leading from the reversing-valve to the cylinder.

In the cylinder A of the engine is mounted to rotate a piston B, secured on a main shaft C, journaled in suitable bearings in the heads of the cylinder A, and in the said piston B are mounted to slide radial piston-heads D, pressed on at their inner ends by springs E to hold the said piston-heads at their outer ends in contact with the inner face of the cylinder A, which inner face is formed of concentric abutments A' A² and working chambers A³ A⁴, of which the abutments A' A² are arranged on the top and bottom of the cylinder, while the chambers A³ A⁴ are located opposite each other on the sides of the cylinder, as plainly illustrated in Fig. 4. The abutments A' and A² are connected with the

chambers A³ A⁴ by gradually-inclined faces A⁵ for the inward and outward movement of the piston-heads D, it being understood that the springs E allow such inward movement of the piston-heads and cause outward movement thereof when the piston B rotates either forward or backward, according to the direction in which the engine is running at the time.

From the upper end of the chamber A³ and the lower end of the chamber A⁴ lead ports a and a' to a common port a², opening into the valve-body F of a reversing-valve in the shape of a four-way valve having a valve-plug F', adapted to be turned by the operator, as hereinafter more fully explained.

The upper end of the working chamber A⁴ and the lower end of the working chamber A³ are connected by ports b and b' with a common port b², leading into the valve-body F at the side opposite the one at which the port a² opens into the said valve-body. (See Fig. 3.)

From the top of the valve-body F leads an exhaust-pipe F² to the outer air, and from the bottom of the said valve-body leads a port c, connected with branch ports c' and c², formed in a steam-chest G, arranged axially on one end of the cylinder A. In this steam-chest G is mounted to rotate a rotary admission-valve H, mounted to slide on and to rotate with the main shaft C, so that when the latter rotates the said admission-valve H rotates with it. As shown in the drawings, the inner end of the shaft C is provided for the purpose with keyways engaged by keys in the hub of the spider or open web at the apex end of the conical valve H.

The rotary admission-valve H is provided in its peripheral wall or rim with spaced narrow ports d, adapted to register with wide ports e, formed in a cut-off valve I, fitted into and mounted to turn in the admission-valve H, and this cut-off valve I is under the control of the operator and is open at its outer end and engaged at this end by the free ends of a spring J, secured at its middle on a shaft K, journaled in the head G' of the steam-chest G, and on the outer end of the said shaft K is secured a handle K', provided with a spring K², adapted to engage one of a series of notches in a notched segment K³, attached to or forming part of the head G'.

(See Fig. 2.) Now by the operator moving the spring K^2 out of engagement with the notched segment K^3 the handle K' becomes unlocked and can then be turned to the right or to the left to turn the cut-off valve I within the admission-valve H to allow the ports d to register for a longer or shorter period with the ports e , to establish a longer or a shorter connection between the interior of the cut-off valve I and the ports c' and c^2 , to cut off the steam sooner or later from the latter, as the case may be.

The live motive agent is supplied to the interior of the valve I by a supply-pipe L, connected with a boiler or other suitable source of motive-agent supply, and when the several ports are in the position illustrated in the drawings then the live motive agent passing into the valve I passes by way of the port e to the corresponding registering port d into the branch ports c' c^2 , from which the motive agent passes to the port c and into the valve-body F at one side of the valve-plug F' to then pass through the port a^2 into the ports a and a' , opening into the chambers A^3 and A^4 , to act on the piston-heads D to turn the piston B in the direction of the arrow x , as plainly indicated in Fig. 4. Thus steam passes simultaneously into the cylinder A at two diametrically opposite points to act on two piston-heads D at the same time. The exhaust-steam in front of the piston-heads D now passes by way of the ports b and b' into the port b^2 and into the valve-body F, from which the motive agent can pass into the exhaust-pipe F^2 , leading to the outer air. By having steam acting on two diametrically opposite piston-heads at the same time all side-wise pressure is equalized.

The cylinder and its piston are preferably of considerable length, while the difference between the diameter of the cylinder at the abutments A' A^2 and that of the working chambers A^3 A^4 is comparatively small, so that the sliding motion of the piston-heads D is reduced to a minimum without reducing the area of the working faces of the piston-heads.

When it is desired to reverse the engine, then the valve-plug F' is turned, and for this purpose the stem of the valve-plug F' is provided with a handle F^3 under the control of the operator and adapted to abut against pins F^4 . (See Figs. 1 and 2.) Now when the handle F^3 is thrown over from the right to the left (see Fig. 2) then the valve-plug F' is shifted to connect the interior of the valve-body F with the exhaust-pipe F^2 and to connect the port c with the port b^2 . The motive agent now passes from the valve-body F by way of the port b^2 to the ports b and b' , which open at diametrically opposite points into the cylinder A, and thereby act on two piston-heads D at the same time to turn the piston B in the inverse direction of the arrow x .

The admission-valve H and the cut-off valve I are preferably made in the shape of frus-

tums of cones to insure a snug fitting of the admission-valve H on its seat in the steam-chest G and a corresponding fitting of the cut-off valve I within the admission-valve H.

The inner end of the shaft C is made hollow and extends into the cut-off valve I, so that the motive agent can pass through the said hollow end and a part go into the outer end of the cylinder A to press against this end of the cylinder and the outside of the flange B^2 of the piston B, and in the latter are formed longitudinally-extending passageways B' , so that the motive agent passing into the outer end of the cylinder can pass by way of the passageways B' to the inner end of the cylinder, thus relieving the flanged end of the piston B of the pressure over these passageways and preventing excessive pressure on the flanged end of the piston, but retaining enough pressure on the flange B^2 to hold the same in steam-tight contact with the annular shoulder A^7 on the cylinder A and also hold the inner end of the piston B in steam-tight contact with the inner end of the cylinder. The end of the piston-heads D extend into the flange B^2 , (see Fig. 5,) and on the end of the piston-heads D, in the said flange, are secured springs D' , pressing with their free ends against the inside of the flange B^2 to force the inner ends of the said piston-heads D steam-tight against the inner end of the cylinder A.

Ready access is had to the valves H and I on simply removing the head G' of the steam-chest G. The admission-valve H is mounted to slide lengthwise on the shaft C (but turns with the latter) to allow snug fitting of the valve H in its seat in the steam-chest G. For a similar reason the outer end of the cut-off valve I is formed with notches engaged by the free ends of the spring J to allow longitudinal movement of the cut-off valve I in the admission-valve H to compensate at all times for wear. The ports c' and c^2 are located opposite each other in the circular valve-seat, and the two ports e in the cut-off valve I are also opposite each other. By this arrangement the side pressure on the admission-valve H and the cut-off valve I is perfectly balanced.

By the arrangement described a rotary engine is produced free from excessive friction, self-adjusting to take up wear at the working parts, and capable of utilizing the steam expansively to any desired degree by setting the cut-off valve I correspondingly relative to the admission-valve H and the ports c' and c^2 .

I do not limit myself to the particular construction shown and described, as it is evident the same may be varied in its minor features without deviating from the spirit of my invention.

Having thus described my invention, I claim as new and desire to secure by Letters Patent—

1. A rotary engine comprising a cylinder, a

piston mounted to turn therein and provided with slidable piston-heads, a rotary admission-valve in axial alinement with the cylinder and rotating in unison with the said piston, a reversing-valve for controlling the motive agent on its passage from the admission-valve to the cylinder, and a cut-off valve for the said admission-valve, as set forth.

2. A rotary engine comprising a cylinder 10 provided at one end with a steam-chest, having oppositely-arranged ports leading to a common port, a piston mounted to turn in the said cylinder and provided with spring-pressed slidable piston-heads, and a rotary admission-valve mounted to turn in the said steam-chest and rotating in unison with the said piston, the said admission-valve being provided with ports registering with the oppositely-arranged ports in the steam-chest, 20 and a reversing-valve between the steam-chest and the cylinder, the common port of the steam-chest opening into the body of the reversing-valve, as set forth.

3. A rotary engine comprising a cylinder 25 provided at one end with a steam-chest having oppositely-disposed ports, a piston mounted to turn in said cylinder, a rotary admission-valve fitting in said steam-chest and rotating in unison with said piston, the said admission-valve being provided with ports registering with both of said oppositely-disposed ports in the steam-chest, and a manually-controlled cut-off valve for the said admission-valve, as set forth.

35 4. A rotary engine comprising a cylinder, a piston mounted to turn therein and provided with slidable piston-heads, a rotary admission-valve in axial alinement with the cylinder rotating in unison with the said piston, and a manually-controlled cut-off valve for the said admission-valve, the said manually-controlled cut-off valve being fitted within the hollow admission-valve and a spring engaging the outer end of the cut-off valve, as set forth.

45 5. A rotary engine comprising a cylinder provided at one end with a steam-chest, a piston mounted to turn in the said cylinder and having slidable piston-heads, a rotary admission-valve in axial alinement with the cylinder and fitted in the said steam-chest, the admission-valve rotating in unison with the said piston, a manually-controlled reversing-valve for controlling the motive agent on its 50 passage from the admission-valve to the cylinder, and a manually-controlled cut-off valve, fitted in the said admission-valve and connected with the motive-agent supply, as set forth.

60 6. A rotary engine comprising a cylinder, a piston mounted to turn therein and provided with slidable spring-pressed piston-heads, a main shaft carrying the piston, a steam-chest into which extends the said main shaft, the 65 said shaft having a passage opening into the steam-chest and communicating by a port with the outer end of the cylinder, and a ro-

tary admission-valve in the said steam-chest and turning with the said main shaft, as set forth.

7. A rotary engine comprising a cylinder, a piston mounted to turn therein and provided with slidable piston-heads, a main shaft carrying the piston, a steam-chest into which extends the said main shaft and provided with oppositely-disposed ports leading to a common admission-port, connected with the cylinder, and a cylindrical rotary admission-valve in the said steam-chest, rotating with the said shaft, the admission-valve being 75 open at one end and provided in its rim with longitudinal ports registering with the ports in the steam-chest, as set forth.

8. A rotary engine provided with a cylinder having opposite fixed abutments, opposite working chambers between the abutments and peripheral inlet and exhaust ports, a steam-chest at one end of the cylinder, and a piston mounted to turn in the said cylinder and having radially-sliding piston-heads, the 80 piston being provided at one end with a flange and also provided with longitudinal passages for the passage of the motive agent from one end of the cylinder to the other, as set forth.

9. A rotary engine provided with a cylinder having opposite fixed abutments, opposite working chambers and peripheral inlet and exhaust ports, a steam-chest at one end of the cylinder, a piston mounted to turn in the said cylinder and having radially-sliding piston-heads, the piston being provided at one end with a flange and also provided with longitudinal passages for the passage of the motive agent from one end of the cylinder to the other, and a shaft carrying the piston 95 and having a hollow end extending into the said steam-chest, the shaft having a port opening into the end of the cylinder containing the piston-flange, as set forth.

10. A rotary engine comprising a cylinder 110 having oppositely-arranged working chambers, a piston mounted to turn therein and having slidable piston-heads, a main shaft for the said piston, a steam-chest at one end of the cylinder, into which projects the said shaft, a rotary admission-valve fitted in the said steam-chest and secured on the said shaft, and a reversing-valve in the passage between the steam-chest and the cylinder, the engine being provided with ports leading from opposite sides of the reversing-valve body and two branch ports connected with each of said first-mentioned ports and leading respectively to the upper end of one of said working chambers and the lower end of the other 115 working chamber, as set forth.

11. A rotary engine provided with a cylinder having opposite fixed abutments, opposite working chambers and peripheral inlet and exhaust ports, a steam-chest at one end of the cylinder, a piston mounted to turn in the said cylinder and having radially-sliding piston-heads, the piston being provided at one 120 end with a flange and also provided with lon-

gitudinal passages for the passage of the motive agent from one end of the cylinder to the other, and a shaft carrying the piston and having a hollow end extending into the said steam-chest, the shaft having a port opening into the end of the cylinder, containing the piston-flange, and the piston-heads extending into the flange, with springs on the end of the piston-heads in said flange, bearing 10 against the inside of the flange, to press the piston-heads steam-tight against the inner end of the cylinder, as set forth.

12. A rotary engine provided with a cylinder having fixed oppositely-disposed abutments and oppositely-arranged working chambers between the abutments, the walls of the abutments and working chambers being connected with each other by inclined faces, a set of ports connecting the upper end of one 20 working chamber and the lower end of the other working chamber with a common port, a second set of ports connecting the other ends of said chambers with a second common port, a reversing-valve for admitting the motive agent to either of said common ports, a piston mounted to turn in the said cylinder and in peripheral contact with the said abutments, and spring-pressed piston-heads mounted to slide radially in the said piston 25 and adapted to engage the walls of the said abutments in the working chambers, as set forth.

13. An engine-valve mechanism comprising a rotary conical admission-valve, having ports 30 in its rim, and a conical manually-controlled cut-off valve, fitted in the said admission-valve and engaged by a spring at its outer end, the said cut-off valve having cut-off ports for register with the ports in the said ad-

mission-valve, the motive agent passing into 40 the said cut-off valve, as set forth.

14. A rotary engine comprising a cylinder provided at one end with a steam-chest, a piston mounted to turn in the cylinder and having slideable piston-heads, a rotary admission- 45 valve fitted in the said steam-chest and rotating in unison with the piston, a cut-off valve fitting in the said admission-valve, a shaft under the control of the operator and journaled in the head of the steam-chest, and a spring 50 secured at its middle on the inner end of the shaft and engaging with its free ends notches in the outer end of the cut-off valve, as set forth.

15. An engine-valve mechanism comprising 55 a steam-chest, a rotary conical admission-valve mounted in the steam-chest and having ports in its rim, a conical cut-off valve fitted in the said admission-valve and having cut-off ports for register with the ports in the 60 said admission-valve, a shaft journaled in the head of the steam-chest, a spring secured at its middle on the inner end of said shaft and engaging with its free ends notches in the outer end of said cut-off valve, and a han- 65 dle on the outer end of said shaft and provided with a spring adapted to engage a notched segment on the head of the steam-chest, the motive agent passing into the said cut-off valve, as set forth.

In testimony whereof I have signed my name to this specification in the presence of two subscribing witnesses.

MARK A. RICE.
